(Cl. D58—17)

To all whom it may concern:

Be it known that I, Leif A. Rowe, a citizen of the United States, residing at Chicago, county of Cook, and State of Illinois, have invented a new, original, and ornamental Design for a Watering Pot, of which the following is a specification, reference being had to the accompanying drawing forming a part thereof, in which:

Fig. 1 is a plan view of a watering pot showing my new design, Fig. 2 is a side elevational view, Fig. 3 is an end elevational view at the spout end of the pot, and Fig. 4 is an elevational view at the handle end of the pot.

I claim:

The ornamental design for a watering pot, as shown.

LEIF A. ROWE.
